DESIGN FOR A NOVELTY FISH LURE

Desire O. Le Moine, Akron, Ohio

Application November 20, 1947, Serial No. 142,683

Term of patent 14 years

(Cl. D31—4)

To all whom it may concern:

Be it known that I, Desire O. Le Moine, a citizen of the United States and a resident of Akron, in the county of Summit and State of Ohio, have invented a new, original, and ornamental Design for a Novelty Fish Lure, of which the following is a specification, reference being had to the accompanying drawing, forming part thereof.

In the drawing:

What I claim is:

The ornamental design for a novelty fish lure, as shown.

DESIRE O. LE MOINE.
